US0D1055888S

(12) **United States Design Patent** (10) **Patent No.:** **US D1,055,888 S**
(45) **Date of Patent:** **** Dec. 31, 2024**

(54) **SPEAKER**

(71) Applicant: **LG DISPLAY CO., LTD.**, Seoul (KR)

(72) Inventors: **Chiyoung Lee**, Paju-si (KR);
Kwangchan Lee, Paju-si (KR);
Jikyoung Kim, Paju-si (KR); **Yeongrak Choi**, Paju-si (KR); **Hyunjung Song**, Paju-si (KR)

(73) Assignee: **LG DISPLAY CO., LTD.**, Seoul (KR)

(**) Term: **15 Years**

(21) Appl. No.: **29/890,998**

(22) Filed: **Apr. 28, 2023**

Related U.S. Application Data

(63) Continuation of application No. 29/767,092, filed on Jan. 20, 2021, now Pat. No. Des. 989,033.

CLAIM

The ornamental design for a speaker as shown and described.

DESCRIPTION

FIG. 1 is a front, right perspective view of a speaker showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded view thereof.

(Continued)

The broken lines showing the remainder of the speaker are directed to environment; the broken lines form no part of the claimed design.
